UNITED STATES PATENT OFFICE.

JOHN H. RING, OF PROVIDENCE, RHODE ISLAND, ASSIGNOR TO GORHAM MFG. CO., OF PROVIDENCE, RHODE ISLAND.

DESIGN FOR A PLATE OR SIMILAR ARTICLE.

Application filed April 8, 1924. Serial No. 9,199. Term of patent 7 years.

To all whom it may concern:

Be it known that I, JOHN H. RING, a citizen of the United States, residing at Providence, in the county of Providence and State of Rhode Island, have invented a new original, and ornamental Design for a Plate or similar article, of which the following is a specification, reference being had to the accompanying drawings, forming part thereof.

Fig. 1, shows in plan view a part of the design, which part is repeated throughout the entire circumference of the plate or similar article.

Fig. 2 is a view partly in section and partly in side elevation of one half of the plate or similar article.

I claim:

The ornamental design for a plate or similar article as shown.

In testimony whereof I have signed my name to this specification in the presence of two subscribing witnesses.

JOHN H. RING.

Witnesses:

S. N. McCCLARENCE,
J. A. MILLER.
